SHOE TREE

Alfred Atlass, New York, N. Y.

Application August 18, 1944, Serial No. 550,059

7 Claims. (Cl. 12—128.2)

This invention relates to new and useful improvements in shoe trees.

More specifically, the invention proposes the construction of a shoe tree characterized by having a part for fitting in the toe of a shoe and a spring-pressed part for engaging the inner sole of the shoe.

Still further, it is proposed to provide a shoe tree as aforesaid for open heel shoes, having a spring energized member adapted to press against the inner sole of the shoe, and a ratchet for coaction with the member to hold it in various positions.

Still further, is proposed to provide a shoe tree having a ratchet as aforesaid in which the spring member is adjustably slidable.

Another object of the invention is to provide a shoe tree for both open heel and closed heel shoes.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a side view of a shoe tree constructed in accordance with this invention.

Fig. 2 is an inverted plan view of the shoe tree of Fig. 1.

Fig. 3 is a rear view of the shoe tree.

Fig. 4 is a section on the line 4—4 of Fig. 3.

Fig. 5 is a sectional view like Fig. 4 but with the spring member of the shoe tree in engagement with the ratchet thereof.

Fig. 6 is an inverted perspective view of a shoe tree constructed in accordance with a modification of this invention.

Fig. 7 is a side view of another shoe tree constructed in accordance with a further modification of this invention.

Fig. 8 is a plan view of the tree of Fig. 7.

Fig. 9 is an inverted plan view of the tree of Fig. 8.

Fig. 10 is a section on the line 10—10 of Fig. 8.

Fig. 11 is a rear view of a toe portion of the tree of Fig. 7.

Fig. 12 is an inverted plan view of a shoe tree constructed in accordance with a further modification of this invention.

The shoe tree shown in Figs. 1—5, according to this invention, is a shoe tree adapted to be used especially with open heel shoes and comprises a body 10 which may be of wood or plastic, and a

spring energized member 11. Body 10 has a concave bottom face 12 and a convex top face 13 shaped in conformity with the inner top face of a shoe at the toe and instep portion thereof. The body has an upwardly extending portion 14 in the rear face 15 of which are formed a plurality of ratchet slots 16.

Member 11 has a portion 17 connected to the bottom face by screws 18, a downwardly and rearwardly extending portion 19 at the end of which is a spherical portion 20 from which extends upwardly a hook 21. Hook 21 terminates in a part 22 adapted to coact with the ratchet slots 16.

The operation of the shoe tree as follows:

The shoe tree is for insertion in the toe and instep portion of a shoe, especially an open heel shoe which has no back for coaction with the cam member of a conventional shoe tree. The shoe tree acts to preserve the shape of the shoe. In order to place the shoe tree in the shoe, a person places his thumb on the portion 14 and his index finger in the hook 21 and squeezes them together. When the shoe tree is in the shoe and the hook is released, the spherical portion 20 presses against the inner sole of the shoe, holding the shoe tree in place. The spherical portion provides an increased friction surface engaging a large surface of the inner sole, thus affording sufficient friction to prevent the shoe tree from working toward the rear of the shoe.

In some types of shoes, especially women's soft shoes of narrow widths, the spring action of member 11 may be too extreme. The pressure exerted by the spherical portion 20 may be moderated by use of the ratchet slots 16. The hook 21 is squeezed toward the portion 14, and the portion 22 is placed in one of the ratchet slots, the ratchet slot holding the spring member 11 compressed. The uppermost ratchet slot is so placed that when portion 22 is disposed therein, the spring action of the member 11 will be entirely ineffective to exert any force against the inner sole of the shoe.

In the modification of the invention shown in Fig. 6, the construction of the shoe tree is similar to that previously described except that portion 17 is slidably mounted in a guide 23 fastened by screws 18' to the bottom face 12' of the shoe tree. This slidable mounting of the member 11' permits adjustment of the portion 20' so that it can be caused to bear in the proper place in the shoe.

In the modification of the invention shown in Figs. 7—11, the shoe tree is devised for use in a

shoe having a closed heel. It includes a body 24 having perforations 25 for permitting air to pass through the shoe when the shoe tree is in it. The body has a concave bottom face 26 and a convex top face 27 of suitable shape to fit in a shoe, body 24 extending only in the toe and instep portion of the shoe. A slot 28 is formed in the rear wall 29 of the body and a threaded shaft 30 is pivotally connected in the slot for vertical swinging by a screw 31.

Another shaft 32 is threaded on shaft 30, shaft 32 having a threaded socket 33 for screwing on the threaded end of the shaft 30. A cam 34 is pivotally connected to the free end of shaft 32 by a screw 35, cam 34 being formed integrally with a hook shaped handle 36, handle 36 being on one side of screw 35 and cam 34 on the other side. The overall length of the shoe tree is adjustable by turning shafts 30 and 32 relative to each other.

The operation of this shoe tree is as follows:

The body 24 of the shoe tree is placed in a shoe and the cam and handle are disposed vertically as shown in Fig. 7, with the cam 34 adjacent the heel of the shoe. The handle is then forced downward against the shaft 32, thereby forcing cam 34 rearwardly into engagement with the heel of the shoe, this movement forcing the body 24 into the toe of the shoe. If the cam 34 does not engage the heel with sufficient force, it may be adjusted by rotating shaft 32 relative to shaft 30.

Shaft 32 can be unscrewed from shaft 30, and body 24 can be used in an open heel shoe if desired. However, when it is desired to have a shoe tree that can be used in either an open heel shoe or a closed heel shoe, it is preferred to employ a shoe tree as shown in Fig. 12. Only the body 24' is shown in Fig. 12, but it will be understood that a shaft 32, cam 34 and handle 36 will be employed with the body when the shoe tree is to be used in a closed heel shoe. The shoe tree of Fig. 12 differs from the shoe tree of Fig. 7 only in that a spring member 11" is attached to the bottom face of the body 24' and ratchet slots 16" are provided in the rear wall of the body 24'. When employing the shoe tree in a closed heel shoe, the member 11" is locked in the uppermost ratchet slot to make it ineffective. When it is employed in an open heel shoe, the shaft 32 is unthreaded from the shaft 30' and the member 11" is released from the ratchet slots, the body 24' then functioning like the body 11 of the shoe tree of Fig. 1.

All of the shoe trees, as aforesaid, except for the shafts, screws and spring members, may be made of wood, plastic or other suitable material. The concave bodies, due to their bottom hollow surface, help the shoes to dry out. Each of the shoe trees may be made in several suitable sizes.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A shoe support for an open heel shoe comprising a body having a concave bottom face, a convex top face similar in shape to the toe and instep portion of the inside of said shoe, and a rear face, ratchet grooves in said rear face, and a spring metal member secured to said bottom face and extending downwardly and rearwardly

from the toe of said body, said member having a spherically shaped portion at its lowermost point adapted to engage the inner sole of said shoe, and a hook extending upwardly from said spherically shaped portion, the free end of said hook being adapted to coat with said ratchet grooves for adjusting the force of said spring member.

2. A shoe support for an open heel shoe comprising a body having a concave bottom face, a convex top face similar in shape to the toe and instep portion of the inside of said shoe, and a rear face, ratchet grooves in said rear face, a guide secured to said bottom face and a spring metal member slidably secured at its front end in said guide and extending downwardly and rearwardly from the toe of said body, said member having a spherically shaped portion at its lowermost point adapted to engage the inner sole of said shoe, and a hook extending upwardly from said spherically shaped portion, the free end of said hook being adapted to coat with said ratchet grooves for adjusting the force of said spring member, said spring member being adapted to slide on said guide to adjust the position of said spherical portion.

3. A shoe tree comprising a body having a concave bottom face and a convex top face similar in shape to the toe and instep portion of the inside of a shoe, a spring metal member secured to said bottom face and extending downwardly and rearwardly from the toe of said body, said member having a spherically shaped portion at its lowermost point adapted to engage the inner sole of said shoe, and a hook extending upwardly from said spherically shaped portion, an extendable rod pivotally secured to said body, and a cam pivotally secured to the end of said rod remote from said body.

4. A shoe tree comprising a body having a concave bottom face, a convex top face similar in shape to the toe and instep portion of the inside of a shoe, and a rear face connecting said bottom and top faces, a slot in said rear face, a threaded bar pivotally connected in said slot for vertical swinging, a rod screwed on said bar, and a cam member pivotally secured to said rod for vertical swinging, said member having a hook portion at one end and a cam member at the other end whereby when said hook member is moved toward said rod, said cam member moves away from the toe of said body.

5. A shoe tree comprising a body having a concave bottom face, a convex top face similar in shape to the toe and instep portion of the inside of a shoe, and a rear face connecting said bottom and top faces, a slot in said rear face, a threaded bar pivotally connected in said slot for vertical swinging, a rod removably screwed on said bar, a cam member pivotally secured to said rod for vertical swinging, said member having a hook portion at one end and a cam member at the other end whereby when said hook member is moved toward said rod, said cam member moves away from the toe of said body, and a spring member secured to said bottom face and depending therefrom adapted to engage the inner sole of a shoe.

6. A shoe tree comprising a body having a concave bottom face, a convex top face similar in shape to the toe and instep portion of the inside of a shoe, and a rear face connecting said bottom and top faces, ratchet grooves in said rear face, a slot in said rear face, a threaded bar pivotally connected in said slot for vertical swinging, a rod screwed on said bar, a cam member pivotally secured to said rod for vertical swinging, said

member having a hook portion at one end and a cam member at the other end whereby when said hook member is moved toward said rod, said cam member moves away from the toe of said body, and a spring member secured to said bottom face and extending downwardly and rearwardly, terminating in a hook having a free end, said free end being adapted to coact with said ratchet grooves to adjust the spring pressure of said member.

7. A shoe tree comprising a wooden perforated body having a concave bottom face, a convex top face similar in shape to the toe and instep

portion of the inside of a shoe, and a rear face connecting said bottom and top faces, a slot in said rear face, a threaded metal bar pivotally connected in said slot for vertical swinging, a hollow rod screwed on said bar, and a wooden cam member pivotally secured to said rod for vertical swinging, said member having a finger hook portion at one end and a cam member at the other end whereby when said hook member is moved toward said rod, said cam member moves away from the toe of said body.
